170,523

TABLE OR SIMILAR ARTICLE

Roy Brown, Chicago, Ill.

Application March 9, 1953, Serial No. 23,963

Term of patent 14 years

(Cl. D80—9)

To all whom it may concern:

Be it known that I, Roy Brown, a citizen of the United States, residing at Chicago, Cook County, State of Illinois, have invented a new, original, and ornamental Design for a Table or Similar Article, of which the following is a specification, reference being had to the accompanying drawing, forming a part hereof.

I claim:

The ornamental design for a table or similar article, as shown.

ROY BROWN.
